US00D829196S

(12) **United States Design Patent** (10) Patent No.: **US D829,196 S**
Kim et al. (45) Date of Patent: ** Sep. 25, 2018

(54) **BRACKET**

(71) Applicant: **SAMSUNG ELECTRONICS CO., LTD.**, Suwon-si, Gyeonggi-do (KR)

(72) Inventors: **Junpyo Kim**, Seoul (KR); **Chanhee Han**, Seoul (KR); **Gyoo-sang Choi**, Suwon-si (KR)

(73) Assignee: **SAMSUNG ELECTRONICS CO., LTD.**, Gyeonggi-Do (KR)

(**) Term: **15 Years**

(21) Appl. No.: **29/606,723**

(22) Filed: **Jun. 7, 2017**

(30) **Foreign Application Priority Data**

Dec. 15, 2016 (KR) 30-2016-0061203

(51) LOC (11) Cl. **14-03**

(52) U.S. Cl.

USPC **D14/238**

(58) **Field of Classification Search**

USPC D8/355, 353, 356; D12/420, 423; D14/238, 452; D25/119, 120, 121

CPC A47G 1/141; A47G 29/00; F16M 11/26; G06F 3/1446

See application file for complete search history.

(57) **CLAIM**

The ornamental design for a bracket, as shown and described.

DESCRIPTION

FIG. 1 is a front perspective view of a bracket showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear and bottom perspective view thereof;

FIG. 9 is a front perspective view thereof, as shown in an alternate configuration;

FIG. 10 is a front perspective view thereof, as shown in another alternate configuration; and,

FIG. 11 is a rear perspective view thereof shown in an example environment.

The broken lines illustrating portions of the bracket form no part of the claimed design. The dot-dot-dash broken lines depict environmental subject matter and form no part of the claimed design.

1 Claim, 11 Drawing Sheets
